CONTROL MECHANISM FOR FLUID AND ELECTRIC COUPLINGS.

1,386,234.

Specification of Letters Patent. Patented Aug. 2, 1921.

Application filed May 22, 1914. Serial No. 840,203.

To all whom it may concern:

Be it known that I, THOMAS R. BROWN, a citizen of the United States, residing at Sparkill, in the county of Rockland and State 5 of New York, have invented new and useful Improvements in Control Mechanism for Fluid and Electric Couplings, of which the following is a specification.

This invention relates to electric train 10 line couplings, and more particularly to an apparatus for controlling the electric train line circuits and fluid pressure train pipe line passages.

Where electric train line couplings provide 15 for a plurality of circuits located at one or both sides of the coupler axis, when counterpart couplings are brought together, the corresponding train line circuits will not be in alinement, since a train line on 20 one side of one coupling will be on the opposite side in the other coupling, as will be evident.

One object of my invention is therefore to provide means for crossing the train line 25 conductors on one coupling, so that when counterpart couplings are brought together, corresponding train line circuits will be in position for registry.

Another object of my invention is to provide 30 a device for controlling the electric train line circuits and means controlled by said device for opening and closing the outlets of the train brake pipe, the signal pipe, and other fluid pressure pipes.

In the accompanying drawings; Figure 1 35 is a diagrammatic view of a control apparatus embodying my invention as applied to two cars and coupled together; Fig. 2 a diagrammatic view illustrating the relative 40 positions of the electric train line switches of counterpart couplings when coupled; Fig. 3 a side view of the switch drum; Fig. 4 a diagrammatic view of a somewhat modified construction embodying my invention; Fig. 5 a transverse section of the mechanism 45 for automatically controlling fluid pressure train lines in conjunction with the electric train line switch control; and Fig. 6 a transverse section of the above mechanism 50 on a different plane.

The control mechanism shown in Fig. 1 of the drawings may comprise a casing 1 containing a switch drum 2 having a plurality of contacts 3 and 4 arranged in vertical

55 pairs and corresponding in number with the number of train line circuits to be provided for. For rotating the drum 2, a pair of stationary pistons 4 and 5 is preferably provided and a movable piston cylinder 6 having attached thereto a rack 7 adapted to mesh with a gear segment 8 carried by the shaft 9 of the switch drum 2. The pistons 4 and 5 are chambered, and within each chamber is a coiled spring 10, adapted to yieldingly resist movement of a movable abutment 11, slidably mounted on a central 60 guide stem 12.

An intermediate dividing wall 13 of the cylinder 6 is normally held in engagement 65 with both of the movable abutments 11, so that the cylinder tends to yieldingly remain 70 in intermediate position between the stationary pistons 4 and 5.

The interior chamber of one of the stationary pistons, such as the piston 4, communicates 75 with a pipe 14 leading to a fluid pressure controlling cock 15 and this chamber also communicates with a pipe 16 adapted to be connected through a coupling to a pipe on the adjoining car when the cars 80 are coupled up. The chamber of the other piston 5 is similarly open to a pipe 17.

A storage reservoir 18 is connected by a pipe 19 to the cock 15 and is charged from the train brake pipe 20 through a pipe 21 85 containing a check valve 22, and having a restricted port 23 communicating with the reservoir.

In order to lock the switch drum 2 in its operative positions, a detent 24 is provided, 90 which is adapted to engage on opposite sides of a projection 25 carried by the gear segment 8. The detent 24 may be operated by fluid pressure and for this purpose is provided with a piston 26 having the chamber 95 27 at one side open to a passage 28 containing a check valve 29 and communicating with a pipe 30 leading to the cock 15. Said chamber is also connected to a pipe 31 having gasket connection in the coupling adapted 100 to register with a corresponding pipe of a counterpart coupling. The opposite side of the piston 26 is subject to a spring 32 tending to hold the piston and the detent 24 in the outer position.

Normally, the detent 24 rests on the outer face of the projection 25, and the springs 10 acting in opposite directions on the wall 13

maintain the cylinder 6 in its intermediate position, in which the switch drum 2 is turned so that the contact fingers 33 do not close any circuits through the contacts 3 5 and 4 of the switch drums and consequently in this position, the electric train line circuits are open.

If it is desired to couple up, the electric train line couplings are first coupled, so as 10 to effect the electrical connection of the train line circuits through the couplings and then the plug valve 34 of the cock 15 is turned to the coupling position on either one of the connected cars. In this position, 15 a cavity 35 in the valve 34 connects pipe 14 with pipe 19, so that fluid under pressure from the reservoir 18 is supplied to the piston chamber of the piston 4 on the car when the cock 15 is operated. The cylinder 6 is then actuated and through the action of the rack 7 and the gear segment 8 the switch drum 2 is rotated in one direction. Fluid supplied to the piston 4, however, also flows through pipe 16 to pipe 17 on the other 20 car and thence flows to the piston chamber of the piston 5. Consequently, on this car, the cylinder 6 is operated to turn the switch drum 2 in the opposite direction.

The relation of the switch contacts and 30 fingers on the counterpart couplings will then be as illustrated diagrammatically in Figs. 2 and 4, where two of the main line circuits are shown.

Referring to Fig. 2 of the drawings, train 35 line circuit *a* of each car is connected to a contact finger 33^a, circuit *b* to finger 33^b and leads *c* and *d*, connected to the electric coupling contact terminals *c'* and *d'*, are respectively connected to fingers 33^c and 33^d.

40 The course of the train line circuit *a* is from the contact finger 33^a on one car through drum contact 4, finger 33^c to lead *c* which is electrically connected by terminals *c'* and *d'* to lead *d* in the coupling on the 45 other car. The circuit continues through contact finger 33^d to drum contact 3 and thence through finger 33^b to train line circuit *a*. Similarly, the *b* circuit is from contact finger 33^b, through drum contact 3, 50 finger 33^d, lead *d*, contact terminals *d'*, *c'*, lead *c*, contact finger 33^c, drum contact 4, and finger 33^b to circuit *b*. The contact terminals are merely shown diagrammatically, but may be supported in any suitable 55 or preferred form of coupler heads.

It will thus be seen that corresponding train line circuits are properly connected by the operation of one of the switch drums so as to cross connect the circuits, and while 60 the above description refers only to two train line circuits, it will be evident that any number of circuits may be controlled by providing the necessary contacts on the switch drum.

65 Since the opposite piston chambers of the

switch controlling mechanism are always connected when counterpart couplings are brought together, it follows that no matter which fluid pressure controlling cock happens to be manipulated, one switch drum 70 will make straight connections while the other is operated to make cross connections.

Upon movement of the switch drum to either operating position, the detent 24 drops into position back of the projection 25 so 75 that the switch drum is locked in position and this obviates the necessity of maintaining fluid pressure on the operating piston cylinder. In order to cut off the air supply to the piston cylinder 6, the valve 34 is provided with a normal coupled position, in which the operating handle is removable and in which the cavity 35 is shifted out of registry with the pipe 14. In this position, said pipe is connected with a cavity 36 in the 80 valve which establishes communication from the pipe 14 to an exhaust port 37, so that the piston chamber of the switch control mechanism is vented to the atmosphere.

The detent 24 may also be provided with 90 a projecting stem handle 38, so that when desired, the switch drum may be released by manually operating the handle 38.

In a coupling, it is desirable to open the electric train line circuits before the cars 95 are separated, and for this purpose, the cock valve 34 has a position in which pipe 30 is connected through cavity 35 with supply pipe 19. Fluid in this position is supplied to piston chamber 28 and this actuates the detent piston 26 and thereby releases the detent 24, permitting the switch drum to return to its neutral position. Fluid is also supplied through the connected pipes 31 to the piston 26 of the counterpart switch control mechanism, so that the detent 24 on each car is operated to permit the switch drum to 100 return to neutral position. The check valve 29 prevents back flow of fluid from pipe 31 to the cock 15 on the car where the cock is 110 not actuated in a coupling, so that there will be no escape of fluid under pressure by flow out of the open exhaust port 37.

By taking the air supply from the reservoir 18, instead of directly from the brake 115 pipe, possible reduction in brake pipe pressure is prevented which might otherwise be sufficient, in some cases, to cause an unintentional application of the brakes.

Another feature of my invention consists 120 in controlling the brake pipe, and signal pipe outlets, so that when the switch drum is operated in uncoupling, the said outlets may be automatically closed while provision is made for holding the brake pipe outlet 125 open upon a break-in-two, so that the usual emergency application of the brakes will be obtained in such event.

For this purpose, a brake pipe outlet controlling valve device is employed compris- 130

ing a casing 39 containing a piston 40 having the chamber 41 at one side connected to a pipe 42 leading to the controlling cock 15, and the chamber 43 at the opposite side in 5 communication with a pipe 44 also leading to the cock 15. The piston 40 is adapted to seat in its opposite extreme positions, so as to prevent flow past the piston and is provided with a stem 45 carrying a valve 46 10 for controlling communication through the brake pipe 20.

The valve 46 is arranged to have a movement relative to the piston 40, so as to permit the valve to seat at all times when the 15 piston 40 is seated. This relative movement may be provided by securing the valve 46 to a valve 47 which controls communication from the brake pipe to the chamber 41.

A spring 48 tends to maintain the valve 20 47 seated and also yieldingly maintains the valve 46 seated when the piston 40 is operated.

For controlling the signal pipe outlet a valve device is provided comprising a casing 50 having a piston chamber 51 containing a piston 52 for operating a valve 53 adapted to control communication through the signal pipe 54.

The piston chamber 51 is connected to a 30 pipe 55 which communicates with pipe 44 leading to the controlling cock 15.

In operation, when the handle of the controlling cock 15 is in either of its coupled positions the pipe 44 is connected by cavity 35 with supply pipe 19, so that fluid under pressure is supplied to piston chamber 43 and piston chamber 51 to maintain the respective pistons 40 and 52 in positions for holding the valve 46 and the valve 53 open. 40 This consequently allows the free flow of fluid through the brake and signal pipes when the cars are coupled up, the piston chamber 41 being connected to the atmospheric port 37 through pipe 42 and cavity 45 36 in the valve 34.

When the valve 34 is turned to either of its uncoupling positions, the pipe 44 is connected to the atmospheric port 37 through cavity 36, while pipe 42 is connected to supply pipe 19 through cavity 35. Fluid under pressure is then supplied to piston chamber 41 while the piston chamber 43 is vented to the atmosphere and consequently the piston 40 is actuated to close the valve 46 and cut 55 off flow through the brake pipe.

The venting of piston chamber 51 also permits the piston 52 to shift so as to close the signal valve 53. The seating of valve 46 also operates to open the valve 47 so that 60 fluid pressure in the piston chamber 41 can bleed into the brake pipe and prevent possible bottling of pressure in the chamber, thereby insuring the prompt opening of the valve 46 when the brake pipe pressure is 65 again raised.

In case of a break-in-two, the piston 40 is held in open position by fluid supplied from reservoir 18 to the piston chamber 43, so that the brake pipe may be vented to the atmosphere to produce an emergency application of the brakes in the usual manner. The fluid in reservoir 18, however, slowly leaks away by flow around the piston stem 45, so that finally the spring pressure on the piston 40 exceeds the fluid pressure in chamber 43 and the piston 40 is thereby operated to close the valve 46. 70 75

According to the modification shown in Figs. 4 and 5 of the drawings, the valves for controlling the outlets of the brake pipe and the signal pipe may be directly operated by a mechanical connection to the electric train line switch drum instead of by fluid pressure, and for this purpose, an additional gear segment 60 may be provided on the 80 switch drum shaft 9, for engagement with gear segments 61 and 62. The gear segment 61 is secured to a shaft 63 provided with a cam 64 having projections 65 and 66 for engaging the stem of a puppet valve 90 67 controlling communication through the brake pipe 20 to the coupling end of the brake pipe. The gear segment 62 is secured to a shaft 68 carrying a cam 69 having projections 70 and 71 adapted to engage 95 the stem of a puppet valve 72 for controlling communication through the signal pipe 54 to the coupling.

When the switch drum is turned to neutral position, in uncoupling, the gear segments 100 are turned by the gear segment 60 so that the flat faces of the cams 64 and 69, which are located between the cam projections, are turned to a position parallel with the ends of the valves 67 and 72. This permits the 105 valves to close and cut off flow through the brake pipe and the signal pipe. After coupling, the switch drum is turned either one way or the other from neutral position and in so turning, the gear segments 61 and 62 110 are rotated so as to bring one of the projections of the cams 64 and 69 into engagement with the respective valves 67 and 72. The valves are thus held open in the coupled position and in case of a break-in-two, the 115 brake pipe is vented to the atmosphere in the usual manner.

In order to provide an independent manual control of the brake and signal pipe outlets, manually operated cocks 73 and 74 may 120 be provided and these cocks may then be operated the same as ordinary angle cocks for manually opening and closing the brake and signal pipes.

Having now described my invention, what 125 I claim as new and desire to secure by Letters Patent is:

1. The combination with a plurality of electric train line circuits having terminals adapted to be connected with the correspond- 130

- ing circuits of another car, of a switch located between the terminal wires and the car circuit wires on each car, and having one position to transversely cross connect 5 said terminal wires with said car circuit wires, and another position to open said circuits, and means for operating one of said switches to one position and the other switch to the opposite position.
- 10 2. The combination with a plurality of electric train line circuits having terminals adapted to be electrically connected with the corresponding circuits of another car, of a switch for controlling said circuits and manually operated means for shifting counterpart 15 switches on connected cars to cross connect the terminals on one car with the train line circuits and straight connect the terminals on the other car with the train line 20 circuits.
3. The combination with a plurality of electric train line circuits having terminals adapted to be electrically connected with the corresponding circuits of another car, of a switch for controlling said circuits having 25 one position for directly connecting the terminals with train line circuits and another position for cross connecting same and means operated from one car for moving 30 counterpart switches to different positions.
4. The combination with a plurality of electric train line circuits having terminals adapted to be electrically connected with the corresponding circuits of another car, of a 35 rotatable switch for controlling said circuits having positions for directly and cross connecting the terminals with the train line circuits, a fluid operated piston device for actuating said switch, a fluid conduit for 40 connecting counterpart piston devices upon the meeting of counterpart couplings, and manually controlled means for supplying fluid to both piston devices to thereby shift one switch to one operating position and the 45 other switch to the other operating position.
5. The combination with a plurality of electric train line circuits having terminals adapted to be electrically connected with the corresponding circuits of another car, of 50 a switch for controlling said circuits having positions for directly and cross connecting the terminals with the train line circuits, a movable abutment operated by supplying fluid under pressure to one side for shifting 55 the switch to one position and by supplying fluid to the opposite side for shifting the switch to the other position, a fluid conduit for connecting opposite sides of counterpart movable abutments upon the coming together 60 of adjacent cars, and means for supplying fluid to one side of the movable abutment.
6. The combination with a plurality of electric train line circuits having terminals 65 adapted to be electrically connected with the

corresponding circuits of another car, of a controlling mechanism for the train line circuits comprising a switch having positions for directly and cross connecting the train line circuits with the terminals, a movable abutment operated by the admission of fluid pressure to opposite sides for shifting the switch to its respective operative positions, and a passage connecting opposite sides of the movable abutments of counterpart 70 controlling mechanisms when cars are coupled together.

7. The combination with a plurality of electric train line circuits, of a switch having two opposite positions for connecting 80 said train line circuits, and an intermediate neutral position in which the circuits are open, means tending to maintain the switch in said neutral position, and fluid pressure mechanism for throwing the switch to either 85 one or the other of its opposite positions.

8. In an electric coupling for cars, the combination of a plurality of contact terminals connected to the respective car line circuits and adapted to engage corresponding 90 contacts of another car when the cars are coupled together, a switch for said circuits having an intermediate neutral position and two opposite operative positions, means normally tending to move said switch to its 95 neutral position, and locking means for holding said switch in either one of its opposite operative positions.

9. In an electric coupling for cars, the combination of a plurality of contact terminals connected to the respective car line circuits and adapted to engage corresponding contacts of another car when the cars are coupled together, a switch for said circuits having an intermediate neutral position and two opposite operative positions, springs for normally holding said switch in its neutral position, locks for positively holding the switch in either one of its opposite operative 100 positions, and fluid pressure means for releasing said locks.

10. In an electric coupling for cars, the combination of a plurality of contact terminals connected to the respective car line circuits and adapted to engage corresponding 115 contacts of another car when the cars are coupled together, a switch for said circuits having an intermediate neutral position and two opposite operative positions, springs for normally holding said switch in its neutral position, a piston for actuating said switch, a valve for controlling the supply of fluid pressure to said piston, and locking means for holding said switch in either one of its opposite 120 positions.

11. In an electric coupling for cars, the combination of a plurality of contact terminals connected to the respective car line circuits and adapted to engage corresponding contacts of another car when the cars are 130

coupled together, a switch for said circuits having an intermediate neutral position and two opposite operative positions, springs for normally holding said switch in its neutral position, a piston for actuating said switch, locks for holding said switch in either one of its opposite operative positions, fluid pressure means for releasing said locks, and a valve for controlling the supply of fluid 10 pressure to said piston and to said locks.

12. The combination with car and electric coupling means including a plurality of electric contact members at each side of the car 15 coupler and circuits leading from said contacts, and a reversing switch to straighten out the circuits after the car is coupled.

13. The combination with car and electric coupling means including contact elements carried thereby and circuits leading therefrom, of a reversing switch for the said 20 circuits, and means for operating the reversing switch to straighten out the circuits after the car is coupled.

14. The combination with counterpart car 25 and electric couplers including circuit connections leading therefrom, of a reversing switch mechanism for the connections from each coupler, and means for operating both switch mechanisms from one car to straighten 30 out the circuits after two cars are coupled.

15. The combination with counterpart car and electric couplers including circuit connections, of reversing switch mechanism for connecting the circuits of each coupler, and 35 means in each car for operating the reversing switch in both cars to make predetermined electrical connections after the cars are coupled.

16. The combination with counterpart car 40 and electric couplers comprising a plurality of electrical contacts at each side of the car coupler and circuits leading therefrom, of electric reversing switch mechanism for each coupler having a separate circuit connection 45 for each contact, and means in one car for operating both of said mechanisms to place the proper connections in circuit through the couplers, the number of circuits being the total of the contacts on both sides of one of 50 the car couplers.

17. The combination with counterpart car couplers, of electric contact-makers carried on each side of each coupler with circuits

leading therefrom, and electric reversing switches for reversing the electric circuit connections after impact of the couplers and operation to make a number of circuit connections through the coupler equal to the total of contact makers on both sides of each car coupler. 55

18. In a car and multiple electric coupler, the combination with a rotatable reversing switch for the electric coupler circuits, and means comprising a pair of fluid pressure devices for rotating the switch in one direction or the other. 65

19. The combination with counterpart car and electric couplers for a plurality of circuits, of a rotatable reversing switch for the 70 circuits of each electric coupler, means for rotating each switch in either direction, and controlling means in each car for rotating the reversing switch in one car in one direction and that in the other car in the other direction. 75

20. The combination with counterpart electric couplers having a plurality of contact makers symmetrically disposed on each side of a center line and circuit connections therefor, of a reversing switch for straight 80 or cross connecting and disconnecting the said contact makers in their circuits, and controlling means in each car for operating the switch in both cars.

21. The combination with an electric coupler having a plurality of circuit connections, of a rotatable switch for straight or cross connecting and disconnecting circuits, and means for rotating the switch a predetermined portion of a complete rotation in 90 either direction to make and break connections. 85

22. In a car and electric coupler including circuits leading therefrom, the combination with a rotatable reversing switch for 95 the electric circuits having a neutral position, and means comprising a pair of fluid pressure devices for rotating the switch in one direction or the other from said neutral position. 100

In testimony whereof I have hereunto set my hand.

THOMAS R. BROWN.
